COUNTER HEIGHT BAR TABLE OR THE LIKE

Gaye P. Noe, P.O. Box 2062,
Jacksonville, Fla. 32203

Filed Sept. 30, 1974, Ser. No. 510,424

Term of patent 14 years

Int. Cl. D6—03

U.S. Cl. D6—27

FIG. 1

FIG. 2

FIG. 3

FIG. 4

FIG. 5

FIG. 1 is a front perspective view of a counter height bar table showing my new design;

FIG. 2 is a top plan view thereof;

FIG. 3 is a bottom view thereof;

FIG. 4 is a cross-sectional view taken along line 4—4 of FIG. 1; and

FIG. 5 is a partial cross-sectional view taken along line 5—5 of FIG. 1.

I claim:

The ornamental design for a counter height bar table or the like, substantially as shown.
